CLAIM

The ornamental design for a light therapy pad, as shown and described.

DESCRIPTION

FIG. 1 illustrates a front perspective view of a light therapy pad;

FIG. 2 illustrates a front view of the light therapy pad thereof;

FIG. 3 illustrates a back view of the light therapy pad thereof;

FIG. 4 illustrates a left side view of the light therapy pad thereof;

FIG. 5 illustrates a right side view of the light therapy pad thereof;

FIG. 6 illustrates a top view of the light therapy pad thereof;

FIG. 7 illustrates a bottom view of the light therapy pad thereof;

FIG. 8 illustrates a back perspective view of the light therapy pad; and,

FIG. 9 illustrates an exploded view of the light therapy pad. The broken lines in the drawings illustrate portions of the light therapy pad that form no part of the claimed design.

1 Claim, 9 Drawing Sheets
